Specification for Design.

Patented June 30, 1914.

Application filed April 6, 1914. Serial No. 830,068. Term of patent 7 years.

To all whom it may concern:

Be it known that we, GEORGE M. BEARDSLEE and IRA L. FRENCH, citizens of the United States, residing at Chicago, in the county of Cook and State of Illinois, have invented a new, original, and ornamental Design for Lighting-Fixtures, of which the following is a specification, reference being had to the accompanying drawing, forming part thereof, the design being more particularly shown applied to the part of a lighting-fixture which may be employed either as a ring or band for a ceiling-plate, as a body-shell, or as a candle-cup.

In the drawing:—Figure 1 is a side elevation of our new design illustrating the same applied to the body shell of a lighting fixture. Fig. 2 is a plan view thereof. Fig. 3 is a side elevation of our new design illustrating the same applied to a candle cup.

We claim:—

The ornamental design for a lighting fixture, as shown.

GEORGE M. BEARDSLEE.
IRA L. FRENCH.
